UNITED STATES PATENT OFFICE.

WILLIAM H. STIFNAGLE, OF BERWICK, PENNSYLVANIA, ASSIGNOR TO AMERICAN CAR AND FOUNDRY COMPANY, OF ST. LOUIS, MISSOURI, A CORPORATION OF NEW JERSEY.

CAR END REENFORCEMENT.

Application filed February 19, 1921. Serial No. 446,534.

To all whom it may concern:

Be it known that I, WILLIAM H. STIFNAGLE, residing at Berwick, in Columbia County and State of Pennsylvania, and being a citizen of the United States, have invented certain new and useful Improvements in a Car End Reenforcement, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is an end elevational view of a mine car fitted with a preferred embodiment of my invention;

Figure 2 is a plan view of the same; and

25 Figure 3 is an isometric view of a detail of the invention.

My invention relates to car end reenforcements devised to prevent distortion of the brake ends of mine cars having distended body portions.

30 One object of my invention is to provide a car end reenforcement and tie adapted to stiffen and connect the ends of the opposite overhanging side portions of mine or other cars.

35 Another object is to provide a skeleton reenforcement of simple design and great strength.

In said drawings, 10 represents a mine 40 car having distended or overhanging body side portions 11 comprising floors 12 and wall portions 13. Between the overhanging body portions 11 are the usual intermediate floor and wall portions 14 and 15 respectively, supported upon the usual running gear (not shown). The body is completed upon provision of end wall boards 16 formed to seat upon floor portions 12 and 14 and between wall portions 13 and 15 and suitably held in position, the whole being held by the usual end stirrup 17 shaped to the contour of the body and secured with bolts 18, or in any other approved manner.

Enclosing the ends of the side walls 13 55 and floors 12 of body portions 11 are gusset

pockets 19 of substantially triangular outline having the web portion 20 with marginal flanges 21 and 22 secured respectively to side walls 13 and floor portions 12. The flanges are provided with openings 23 to receive suitable fastening means, preferably taking those used for securing the end stirrup 17 to the body as shown in the drawing.

The pockets 19 are connected by a tie bar 24 extending across the car end and rigidly 60 secured to the webs 20 of the pockets by rivets 25, or in any other way. A substantial portion of the tie bar 24 overlaps a pocket 19 at each end and is secured along its overlapping length to the web 20 of the 70 adjacent pocket to prevent relative rotation of said parts. The web 20 of each pocket functions to maintain a fixed angular relation between adjacent wall and floor portions of the car body.

75 The arrangement of such pockets in connected pairs further operates to preserve the integrity of the car end as a whole and prevent any tendency on the part of the extended portions to sag. The pockets extend 80 above and below their respective points of connection with the tie bar 24 to equalize the load stresses on said pockets and insure a balanced pull on the tie bar.

When in position on the brake end of the 85 car the device lies well against the end wall of the car, protecting the ends of the overhanging sides from injury, and preventing distortion of the car body under the severe racking stress of service. The device has 90 no protruding parts that would in any way interfere with the application of the brake control mechanism.

What I claim is:

1. A car end reenforcement comprising a 95 pair of pocket gussets and a connecting member for said gussets carried by the webs of said gussets.

2. A car end reenforcement comprising a 100 pair of pocket gussets and a connecting member, said gussets having portions extending above and below said connecting member.

3. A car end reenforcement comprising a 105 pair of flanged pocket gussets and a connecting member, said gussets having their flanged portions extending above and below said connecting member.

4. In an end reenforcement for cars having 110 distended body side portions and an end

wall, pocket gussets enclosing one end of said distended side portions, and a connecting member for said gussets traversing the end wall.

5. In a car having distended body side portions and an end wall, side wall and floor portions outlining said distended body portions, pocket gussets enclosing one end of said distended side wall and floor portions, and a connecting member for said gussets traversing the end wall.

6. In a car end structure for cars having distended side wall and floor portions, a pair of pocket gussets enclosing the ends of said 15 distended side wall and floor portions, and means connecting said pockets.

7. In a reinforcement for car ends, a pair of substantially triangular gussets having upright marginal flanged portions, lower 20 marginal flanged portions extending laterally from said upright marginal portions, and a tie bar connecting said gussets, said tie bar having rigid connection with said gussets at a point above said lower marginal

flanged portions and below the upper ends 25 of said upright marginal flanged portions.

8. A car end reenforcement comprising a pair of flanged pocket gussets, car body members secured to said flanges and a connecting member joining the webs of said 30 gussets.

9. A car end comprising end, side and floor members, pocket gussets connecting said side and floor members and means connecting said gussets independently of said 35 end members.

10. A car end comprising end, side and floor members, pocket gussets reinforcing the corners formed by said members and means joining the gussets of each car end 40 independently of the car end members.

In witness whereof I have hereunto set my hand in the presence of two witnesses.

WILLIAM H. STIFNAGLE.
